UNITED STATES PATENT OFFICE.

OSCAR GILBERT LEE AND FRANCIS MARION OSBORNE, OF WASHINGTON, PENNSYLVANIA.

MINE-ELEVATOR CAGE.

1,221,754.

Specification of Letters Patent. Patented Apr. 3, 1917.

Application filed October 16, 1916. Serial No. 125,921.

To all whom it may concern:

Be it known that we, OSCAR GILBERT LEE and FRANCIS MARION OSBORNE, citizens of the United States, residing at Washington, 5 in the county of Washington and State of Pennsylvania, have invented certain new and useful Improvements in Safety Devices for Mine-Elevator Cages; and we do declare the following to be a full, clear, and 10 exact description of the invention, such as will enable others skilled in the art to which it appertains to make and use the same.

This invention relates to new and useful 15 improvements in safety devices for mine elevator cages and the primary object of the invention is to provide effective means normally held out of operation when the hoisting mechanism of the elevator is working, but automatically thrown into action when 20 the hoisting rope or any of its supports break, or the elevator reaches the bottom of the shaft, to lock the same.

Another object of the invention is to provide a device of this character which is 25 easily and simply constructed, inexpensive to manufacture, and one which will be very efficient in operation.

With these and numerous other objects in view, our invention consists of the novel 30 features of construction, and the combination and arrangement of parts which will be herein referred to and more particularly pointed out in the specification and claim.

In the accompanying drawings:—

35 Figure 1 is a side elevation of a portion of an elevator cage provided with the improved safety device, with parts broken away and in section;

Fig. 2 is a vertical transverse section on 40 line 2—2 of Fig. 1;

Fig. 3 is a horizontal section on an enlarged scale, taken on line 3—3 of Fig. 1;

Fig. 4 is a detail transverse section, with 45 the parts in the position they assume when the cage supporting cable is broken.

Fig. 5 is a detail horizontal section on line 5—5 of Fig. 1.

In describing our invention, we shall refer 50 to the drawings in which similar reference characters designate corresponding parts throughout the several views, and in which in Fig. 1, we have shown the safety device in inoperative position, applied to the head beam of a conventional type of elevator cage ordinarily used in mines. The elevator cage

which is designated by the numeral 1 is slideable vertically on guide rails 2 on opposite sides of the same, and the said cage is operated by a single hoisting cable 3.

Secured to the head beam of the elevator cage which is designated by the numeral 4 is the preferred type of safety catch, although if desired, any safety arrangement embodying the general principles herein set forth may be used with this invention. The 60 safety catch shown in the accompanying drawings comprises a pair of rock shafts 5 positioned on opposite sides of the head beam, and which project therefrom having locking pawls 6 on their opposite ends that 65 are adapted for engagement with the sides of the rails 2 on which the cage slides. These shafts 5 are connected intermediate their ends with a leaf spring 7 positioned beneath the head beam 4, and normally tending 70 to hold the locking pawls into engagement with the rails. The connection between the rock shafts and the leaf spring is of any desired type, that is sufficient to rock 75 the shafts when the spring moves, to lock the 80 device.

The elevator cage is supported in the shaft by means of a pair of chains 8 which have their lower ends connected to the head beam, and are connected at their upper ends by a 85 U-shaped member 9. Projecting downwardly through the U-shaped member 9 is a top bolt 10 which has its upper end connected to the hoisting cable 3, and has on its lower portion that projects through the 90 U-shaped member a coil spring 11.

Disposed in vertical alinement with the top bolt 10 and projecting upwardly through the head beam 4 of the elevator cage is a vertically disposed rod 12, which has its lower 95 end secured to the leaf spring 7, and which is slidably mounted through said beam. On the upper end of the rod 12 is formed an eye 13 for a purpose to be hereinafter more fully described. This eye 13 extends a short 100 distance above the head beam 4 and is disposed in vertical alinement with the bottom of the top bolt 10 that is secured to the hoisting cable.

Our present type of safety device embodies a new and novel type of connection between the vertical rod 12 and the top bolt 10, as will be hereinafter fully described. This connection comprises a chain 14 which is normally positioned vertically between 110

these two parts and extends approximately the entire distance between the same. Secured to the lower end of the chain 14 is a clevis 15 which has its lower end connected 5 by means of a horizontally extending bolt 16 in the eye 13 at the top of the rod 12. Mounted on the lower end of the top bolt 10 is an additional clevis 17 which when in position, surrounds a locking nut 18 on said 10 bolt and securely holds the same in position. The upper end of the chain 14 is connected to a bolt 19 extending through the lower end of the clevis by means of a separate link 20 that has an enlarged upper portion 15 surrounding the bolt, and extending between the arms of the clevis. The lower end of this link is connected with the upper link of the chain 14 and forms a secure connection between the parts.

20 From the foregoing description, it will be obvious that the safety device used on this type of elevator is connected with the hoisting cable by a single chain. The operation of the safety device is essentially such as is 25 ordinarily used in devices of this character. During the operation of the elevator cage when the hoisting cable is taut, the spring 7 is compressed owing to the fact that the cable is connected through the top bolt 10, 30 chain 14 and clevises with the vertical rod 12 that has its lower end secured to said spring. When in this position, the safety locking pawls 6 will be held in inoperative 35 position, that is, away from the rails 2, but upon breakage of the cable, or when the elevator cage reaches the bottom of the shaft, this cable will be released, and the spring will resume its normal position thereby 40 driving the pawls into engagement with the guide rails and locking the elevator.

In other devices of this character, a cumbersome structure has been ordinarily used to connect the top bolt with the safety device, but the construction employed by us, owing to 45 its extreme simplicity, makes a very efficient

connection of this character. The clevises at either end of the connecting chain 14 allow the chain to drop upon the top beam of the elevator cage without placing any undue pressure upon the upper portion of the vertical rod 12. The clevis 17 that is secured to the lower portion of the top bolt 10 locks the nut on the lower end of said bolt in position, and prevents the same from working therefrom.

55

From the foregoing description, the construction and operation of our improved safety device for mine elevator cages, the manner of applying the same to use and the operation thereof will be readily understood 60 and it will be seen that we have provided a simple and efficient means for carrying out the objects of the invention.

65

We claim as our invention:—

The combination with an elevator cage 65 having a single hoisting cable, chains secured to the head beam of said cage, a top bolt connecting the chains and cable, a safety catch for said cage, a spring to operate the same, a vertical rod extending upwardly from the head beam of cage and having its lower end connected with the spring, of a chain vertically disposed when the cage is in operation and extending between the vertical rod and top bolt, a clevis 70 connecting the lower end of said chain with the upper end of the vertical rod, a nut on the lower end of the top bolt, and an additional clevis adjacent the lower end of the top bolt adapted to lock the nut thereon in 75 position and connecting said bolt with the upper end of the chain.

80

In testimony whereof we have hereunto set our hands in the presence of two subscribing witnesses.

OSCAR GILBERT LEE.

FRANCIS MARION OSBORNE.
